CLAIM

The ornamental design for the stance training device, as shown and described.

DESCRIPTION

FIG. 1 is a top view of a stance training device showing my new design;

FIG. 2 is a front view thereof with legs extended, the rear view being a mirror image;

FIG. 3 is an enlarged view thereof;

FIG. 4 is an enlarged front view thereof with legs folded, the rear view being a mirror image;

FIG. 5 is a right side elevational view thereof, the left side elevational view being a mirror image;

FIG. 6 is a bottom side view thereof; and,

FIG. 7 is the isometric view of a stance training device. The figure of the baseball player shown in broken lines in FIG. 7 is for illustrative purposes only and forms no part of this invention.
